WATER SOFTENER CABINET

Walter F. Hagman, Kokomo, Ind., assignor to Globe American Corporation, Kokomo, Ind., a corporation

Application December 13, 1954, Serial No. 33,525

Term of patent 14 years

(Cl. D16—2)

The figure is a perspective view of a water softener cabinet, showing my new design, the side not shown being substantially like the side shown in the drawing.

I claim:

The ornamental design for a water softener cabinet, as shown and described.
